CLAIM

The ornamental design for an insulin pen holder, as shown.

DESCRIPTION

FIG. 1 is an upper perspective view of the article in which the design is embodied.

FIG. 2 is a front view of the article of FIG. 1.

FIG. 3 is a back view of the article of FIG. 1.

FIG. 4 is a side view of the article of FIG. 1; and,

FIG. 5 is a lower perspective view of the article of FIG. 1. Characteristic features of the article's design are trapezoidal configurations and positionings of peripheral walls, upper surface, and pen socket structures.
